CLAIM

The ornamental design for an athletic ball hurler, as shown
and described.

DESCRIPTION

FIG. 1 is a back elevational view of a athletic ball hurling
device showing my new design;

FIG. 2 is a rear elevational view thereof;

FIG. 3 is a top plan view thereof;

FIG. 4 is a bottom plan view thereof;

FIG. 5 is a right side elevational view thereof, the opposite
being a mirror image; and,

FIG. 6 is a perspective view thereof.
